CLAIM

The ornamental design for a drop axle for towed vehicles such as boat and utility trailers, substantially as shown and described.

DESCRIPTION

FIG. 1 is a side elevational view of a drop axle for towed vehicles such as boat and utility trailers showing my new design, the opposite side being a mirror image thereof.

FIG. 2 is an enlarged fragmentary bottom perspective view of one end thereof.

FIG. 3 is an enlarged sectional view thereof taken along line 3—3 of FIG. 1.

FIG. 4 is an enlarged fragmentary top plan view of one end thereof.

FIG. 1

FIG. 4

FIG. 3
